VALVE SLEEVE TOOL

Alvin C. Gober, Wichita Falls, Tex.

Application September 12, 1950, Serial No. 184,413

2 Claims. (Cl. 29—265)

1

This invention relates to improvements in valve sleeve tools and more particularly to a tool for removing piston sleeves in hydraulic valve tappet systems.

With the advent of modern high speed internal combustion engines, such as used in automobiles, the arrangement of spacing valve tappets from the valves or push rods is becoming obsolete, and is being replaced by a system wherein the oil pressure exerted from the engine enters a cylinder within the valve tappet system and passes through the valve into a chamber to force a piston sleeve upward into contact relation with the valve or valve push rods. In so doing the clearance between the tappet and the valve or valve push rod becomes zero, eliminating the usual noises present when a valve tappet is a spaced distance from the end of the valve or valve push rod. Due to foreign matter, gum in the oil, and to heat, the sleeve piston frequently sticks and does not permit the oil to maintain the push rod or tappet in contact with the end of the valve, which necessitates the removal of the valve tappet member to free the sleeve piston therein so that it can function properly.

Heretofore, the removal of the sleeve piston resulted in damage thereto and to the associated parts, which frequently meant that the parts had to be discarded and replaced which is expensive, time consuming and inconvenient.

The present invention provides a tool that readily and efficiently removes the piston sleeve from the valve tappet without damage thereto or to the associated parts, and makes the piston sleeve or other parts accessible for cleaning and repair.

An object of this invention is to provide a tool that will readily and effectively remove the hydraulically actuated piston sleeve from the valve tappet member when such sleeve piston has become stuck.

Another object of this invention is to provide a piston sleeve removing tool for hydraulic valve tappets that is simple in construction, efficient and self contained, and which has a guide to cause engagement of the tool with the piston sleeve.

Still another object of the invention is to provide a uniform, compact tool that has a self-centering arrangement so as to hold the valve tappet in aligned centered relation while the piston sleeve is being removed, thereby eliminating danger of damage to the piston sleeve or to the associated parts.

With these objects in view, and others that will 55 manifest themselves as the description proceeds, reference is to be had to the accompanying drawings, in which:

Fig. 1 is a side elevational view of the device embodying the invention;

Fig. 2 is a longitudinal sectional view through the tool and valve tappet assembly, with parts shown in elevation and with parts broken away and shortened to illustrate the details of construction;

Fig. 3 is an enlarged fragmentary view, partly in elevation and partly in section of the lower end of the tool and showing the latch mechanism;

Fig. 4 is a perspective view of an expanding lock ring that holds parts of the tool together during normal operation;

Fig. 5 is a plan view of the tool; and

Fig. 6 is a sectional view taken on the line 20 6—6 of Fig. 3, looking in the direction indicated by the arrows.

With more detailed reference to the invention as illustrated in the annexed drawing, the numeral 1 designates a threaded body of the tool, which has an outwardly extending handle 2. The body 1 has a threaded axial opening 3 in which a threaded stem interengages. The threaded stem 4 has a nut 5 threadably engaging the stem and is locked in place by a set screw 6.

The opposite end of the stem, as indicated at 7, is preferably left unthreaded for a spaced distance and is shouldered at 8, as will best be seen in Figs. 2 and 3. The lower end of the stem, as shown in Figs. 1, 2, 3 and 6 is tapered at 9 which insures the ready insertion of the tool into the piston sleeve 10 which is to be removed. The threaded stem 4 has a spring latch mechanism 11 the end of which is beveled at 12. The opposite end of the latch preferably forms a head 13 which is of elongated shape so as to insure the bevel portion 12 of the latch being maintained in the relation as shown in Figs. 1, 2 and 3. A spring 14 is provided within a recess 15 in the lower end of the stem 4, which spring is retained in place by a plug 16.

The spring 14 may be of elongated shape, such as oval or the like, so as to fit into the recess 15 to urge the latch 11 outward.

The body 1 has a recess 17 in the lower side, which recess has an annular groove 18 therearound. The inner end of the recess 17 terminates in a squared shoulder 19. A sleeve 20 is secured to the body 1 by means of a snap ring 21 which is depressed into peripheral groove 22 in sleeve 20 so that upon sliding the sleeve 20 into

recess 17, the snap ring 21 will expand outwardly to engage annular groove 18 and since the snap ring 21 is of sufficient width to abridge the recess between the periphery of the sleeve 20 and the inner diameter of said recess, thus the two members will be secured together. The sleeve 20 and the body 1 are interengaged to permit relative movement therebetween which will enable the body 1 and handle 2 to be rotated while maintaining the stem 4, tappet T and sleeve 20 against rotation.

The tappet T has a peripheral groove 23 there-around, which groove registers with an oil passage (not shown) in the engine, which permits the oil to circulate around the peripheral groove 23 and to pass into the sleeve through hole 24 formed in the valley of the groove. The oil then passes into a peripheral groove 25 formed around the outer periphery of piston sleeve 10 and through a hole 26 into the interior of the piston sleeve and by a valve 27 in the lower end of the piston sleeve into a chamber therebelow, to cause the piston sleeve to raise upward against a lock ring which may be positioned in annular groove 28 which normally restrains the piston sleeve 10 from upward movement beyond this ring. The hole 26 in piston sleeve 10 is a predetermined distance from the upper face thereof. The tool's latch member 11 is so spaced from shoulder 8 that, upon seating of shoulder 8 on the upper face of the piston sleeve 10, the latch will be circumferentially aligned with the hole 26, so upon rotation of the stem 4, the latch 11 will come into radial alignment with the hole 26, which latch is depressed and the spring 14 will urged the latch outward into engagement with hole 26 when in alignment therewith. With the latch 11 engaged in the hole 26, the sleeve 20 may be seated upon the upper face of tappet T and the handle 2 rotated while tappet T and sleeve 20 are held against rotation, which will normally hold stem 4 against rotation, as the piston sleeve 10 being removed will usually be stuck. However, the stem 4 may be held against rotation by using a wrench on nut 5. By exerting turning action on handle 2, the stem will be lifted upward by the action of screw threaded stem 4, and since the hole within the sleeve 20 is slightly larger than the external diameter of the piston sleeve 10 being removed, the sleeve may be withdrawn from the valve tappet T.

The sleeve 20 is beveled at 27' so as to guide the tappet T into an annular shoulder recess 28' which centers the tappet T with respect to the stem 4 of the tool. After the piston sleeve 10 is removed from the tappet T, a slender instrument may be inserted through hole 26 to depress latch 11 until the sleeve 10 becomes disengaged therefrom. This enables the sleeve to be removed from the tool thus freeing it for reuse.

It is to be appreciated that a tool of this character may be easily and readily used for the removal of the piston tappet sleeves, and while primarily used on automobile engines, it is to be understood that the tool can be applied for use on any internal combustion engine.

While the tool has been described in some detail in one embodiment thereof, it is to be understood that changes may be made in the minor details of construction without departing from the spirit of the invention as claimed.

Having thus clearly shown and described the invention, what is claimed as new and desired to secure by Letters Patent is:

1. In a tool for removing stuck piston sleeves from valve tappet members in hydraulic valve systems a bored and internally threaded body having a handle protruding therefrom, a counterbore formed in and end of said body and in axial alignment with the threaded portion thereof, an annular groove formed in the wall of said body opening into the aforesaid counterbore, a sleeve adapted to be positioned in said counterbore, a peripheral groove formed around said sleeve, said annular groove and said peripheral groove being adapted to register when said sleeve is seated in said counterbore, a lock ring interposed in said peripheral groove and said annular groove so as to retain said sleeve and said body against relative axial movement while permitting relative rotary movement, a threaded stem extending through said body and threadably engaging the same and protruding therefrom, a resiliently pressed lateral finger protruding from said threaded stem for engagement with said piston sleeve in a valve tappet member, shoulder gauge means on said threaded stem to limit the distance said stem carrying said lateral finger extends axially into said piston sleeve so said lateral finger will register circumferentially with a hole in said piston sleeve.
2. In a tool for removing stuck piston sleeves from valve tappet members in hydraulic valve systems, a bored and internally threaded body having an outstanding handle, a counterbore formed in and end of said body, an annular groove formed in the wall of said body intermediate the length of said counterbore, a sleeve having a peripheral groove formed near the end thereof, which sleeve is fitted into said counterbore so said peripheral groove and said annular groove are in register, an outwardly expanding resilient lock ring adapted to be pressed within said peripheral groove in said sleeve so as to spring outward to interengage said annular groove in said body when said grooves are in register so as to secure said body and said sleeve against axial movement while permitting relative turning movement between said body and said sleeve, a counterbore formed in the opposite end of said sleeve so as to receive an end of said valve tappet member and axially align said valve tappet member with said sleeve and with said body, a threaded stem extending through said body and threadably engaging same and protruding therefrom and into said sleeve, the protruding end of said threaded stem being reduced and having a shoulder formed thereon, and a spring pressed lateral finger protruding from said reduced portion of said threaded stem for engagement with a piston sleeve in said valve tappet when said finger is in register with a hole in said piston sleeve to enable the removal of said piston sleeve from said valve tappet member upon rotation of said handle on said body.
